UNITED STATES PATENT OFFICE.

JOHN AUGUST WALLER, OF HIGHLAND PARK, ILLINOIS, ASSIGNOR TO EXPANDED WOOD LATH CORPORATION, OF COOK COUNTY, ILLINOIS, A CORPORATION.

EXPANDED WOOD LATH.

1,314,106.

Specification of Letters Patent. Patented Aug. 26, 1919.

Application filed March 28, 1918. Serial No. 225,169.

To all whom it may concern:

Be it known that I, JOHN A. WALLER, a citizen of the United States, residing at Highland Park, in the county of Cook and State of Illinois, have invented certain new and useful Improvements in Expanded Wood Lath, of which the following is a specification.

My invention relates to building material and construction and has particular reference to expanded wood lath. The general objects of the invention are to provide wood lath in a form of construction which may be manufactured at comparatively small cost compared with expanded metal forms, in both amount of material and labor; to provide expanded lath which will firmly adhere to plaster, cement or concrete, and to greatly augment the speed of construction.

More particular objects of this invention are to provide wood lath with an undercut key which will save in plastic material with which it is coated; to provide expanded lath that may be nailed into place by driving nails through the lath itself; to provide a lath that requires no furring, that may be made rapidly with a battery of ordinary circular saws and provide connective ligaments or ribs that run with the grain of the wood; that may be sold at about one-third the cost of metal lath; that will not rust; that will adhere to tar paper and other sheet coating which may be made a part of the lath as a single article of manufacture so that lath and sheathing may be applied at the same time in the same manner as individual strips of lath are applied singly; to provide a lath that will resist the radiation of heat from a building; that will take coatings of asphaltum so that the lath may be advantageously employed for outer walls of buildings; that may be fitted into a coved ceiling on an even curvature and without causing breakage; that will yield about four square feet of lath out of each square foot of timber; to provide a form of lath suitable for poultry boxes and the like for which wood is the most acceptable material; to provide a lath that will not color the plastering through rust and corrosion; and to provide a lath of light weight with the above named qualities that will be improved in keeping qualities by the coating applied to it, such as the acid of the mortar acting as a preservative on wood where iron would rust and deteri-

orate both itself and the coating applied to it.

With the above-named general objects in view my invention consists in the general construction, combination and arrangement of parts, all as hereinafter described in detail, illustrated in the accompanying drawing and more particularly pointed out in the appended claims.

In the drawing—

Figure 1 is a plan view of a section of expanded lath made up of a half dozen ordinary lath strips which may be nailed on as a single piece.

Fig. 2 is a section taken on line 2—2 of Fig. 1.

Fig. 3 is a plan view of a blank or thin board sawed preparatory to expansion.

Fig. 4 is a modification or extension of Figs. 1 and 2, showing a combination of lath and sheathing as a single article of manufacture.

Fig. 5 is a section taken on the line 5—5 of Fig. 4.

In the several views 2 represents in Fig. 3 a board of about one-quarter inch thickness in which has been sawed a plurality of cuts 3, 3 to leave ribs 4 and individual strips of lath 5 connected by said ribs when expanded as in Figs. 1, 2, 4, and 5. In Figs. 1 and 2 the individual strips of lath are held expanded by metal strips 6 bent U-shape into spaces 7 between the spaced-apart strips as shown in Fig. 2. In Figs. 4 and 5 the individual laths 4 are held spaced apart by a coating of paper or sheathing 8, cemented on with asphaltum or other suitable adhesive material 9.

The individual lath, or strips of lath 5, are rabbeted or under-cut on their rear sides as shown in Figs. 2 and 5, and their connecting ribs 4 are produced, as shown first in Fig. 3, by making a series of parallel saw cuts 3 formed in one or more rows. If the lower end of each of these saw cuts is termed the initial end and the upper end the terminal end, each cut begins substantially near the middle portion and at one side of an adjacent saw cut and terminates near the middle portion and at the opposite side of another adjacent saw cut. Each saw cut passes between the adjacent and opposite ends of another pair of saw cuts and each saw cut overlaps substantially half of two adjacent saw cuts of a row. In Fig. 3

five such rows of saw cuts are shown with the result in the remaining figures of five strips of lath with diagonally or slantingly extending connecting ribs all of which are substantially parallel and present uniformity in the lines of obstruction to mortar, cement or other plastic material that is applied to the expanded board as a whole. The manner in which said saw cuts are made makes the grain of the rib run parallel with the grain of the lath at the juncture between rib and lath strips. In other words the lath and the rib form a continuous or unbroken wood grain. Expanded wood lath, unlike expanded metal lath, adheres firmly to the plastic material and instead of deteriorating, rusting or corroding from the coating and coloring it, the wood lath is improved in keeping qualities by such coating. The light weight and flexibility that is made uniform by the uniformity of cuts and parallelism of arrangement of parts, facilitates more rapid work of construction than is possible with expanded metal lath through which nails cannot be driven to secure anchorage in the most convenient and acceptable points of wall support for the lath. The light weight and uniform flexibility of my improved wood lath also adapts it most advantageously for adjustments to bends or curves such as ceiling coves and the like.

Having thus described my invention, I claim as new and desire to secure by Letters Patent—

1. A wood lath consisting of a board cut by a series of parallel saw cuts into lath strips and extended apart leaving connecting ribs, which extend diagonally from strip to strip, said saw cuts being arranged in a row and each cut terminating at the middle and near an adjacent saw cut.

2. Expanded wood lath consisting of a series of strips of lath formed by making

rows of diagonal and parallel saw cuts 45 through a board, said saw cuts arranged at a slant to the edges of the board and each saw cut in a row beginning near one side of an adjoining saw cut at substantially its middle portion and ending at the opposite 50 side of another adjacent saw cut, the strips of lath thus formed being drawn apart or expanded and the rows of saw cuts leaving connecting ribs between said strips.

3. An expanded wood lath consisting of 55 a thin board sawed into rows of parallel strips and strip connecting ribs, said strips being expanded apart and said ribs extending diagonally in one direction from one strip to another, each beginning opposite the 60 middle portion of one adjacent saw cut and extending to the middle portion and adjacent to another saw cut.

4. A wood lath consisting of a board having 65 rows of saw cuts therethrough, each saw cut being inclined relative to the edges of the board and beginning adjacent to the middle portion of another saw cut and passing between the ends of other similar saw cuts, said board being expanded and forming 70 strips of lath and diagonal connecting ribs between said strips.

5. As an article of manufacture an expanded wood lath and sheathing consisting 75 of a board having one or more rows of parallel saw cuts therethrough, each saw cut beginning at one side of one saw cut and ending at the opposite side of another saw cut, said saw cuts forming diagonally extending connecting ribs between adjacent strips of 80 lath so formed, said lath having at one side rabbeted edges forming key grooves and a cover of sheathing and the like secured to said one side and holding said lath spaced apart.

In testimony whereof I have hereunto signed my name.

JOHN AUGUST WALLER.
